SIFTING APPARATUS

Royal V. Ward, San Bernardino, Calif.

Application June 17, 1942, Serial No. 447,339

14 Claims. (Cl. 209—237)

This invention relates to and has for an object the provision of an improved sifting apparatus by means of which analyses and tests may be made of comminuted material, sand, gravel and other matter, and in which a motor driven means is provided for simultaneously operating a plurality of sifters in such a manner that the more finely divided elements will be gradually moved downwardly by gravity and agitation from the topmost sieve of the stack to the lowermost tray.

A particular object is to provide an apparatus for the purpose described which embodies a novel and highly effective sifting means capable of producing primary oscillations of the stack of sieves or trays as well as secondary or counter oscillations thereof, so that the primary oscillations will effect the sifting of the material in the manner usually accomplished by hand or machine driven elements while the counter oscillations will prevent the piling or stacking of the material at the margins of the trays and thereby serve to maintain a substantially uniform level of the material at all times.

Other objects may appear as the description progresses.

I have shown a preferred form of apparatus embodying my improvements in the accompanying drawing, subject to modification, within the scope of the appended claims, without departing from the spirit of my invention. In said drawing:

Fig. 1 is a side elevation of an assembled machine;

Fig. 3 is an elevation of the same as seen at right angles to the plane of Fig. 1;

Fig. 2 is a top plan view of the same;

Fig. 4 is a sectional plan on line 4—4 of Fig. 1; and

Fig. 5 is a sectional plan on line 5—5 of Fig. 1.

In a preferred form of apparatus capable of economical production, as herein shown, the machine is supported on a base 1 having a vertically disposed column 2 extended therefrom to which is attached a vertical standard 3 herein shown as of right angular cross section. Said standard is rigidly secured to column 2 as by means of bolts 4, 4, and a motor 5 is supported on the column 2 as by means of a bracket 6 extended laterally from the column and suitably secured thereto.

Standard 3 has a pair of vertically spaced arms 7 and 8 rigidly attached thereto at its top and bottom portions which serve to rotatably support a tubular spindle 9 as by means of suitable bearings 10 and 11, respectively. A pair of arms 12 and 13 are carried by spindle 9, at the bottom and top respectively, for the purpose of opera-

tively supporting a plurality of sifting trays, as shown in Fig. 1, as at 14, 14 etc., which are mounted so that each one nests within the next lowest unit and said lowest tray similarly nests in a screenless tray, as at 15, at the bottom of the stack for receiving the final products of each sifting operation for the purpose of analysis and test. Usually the top of each tray 14 and 15 has a bead 16 (Fig. 1) around its upper lip with a recess therewithin to receive the bottom of the next adjacent tray and thereby prevent the dislodgement of the trays from their nested positions during the sifting operations, and the uppermost tray 14 carries a cover 14a.

10 The stack of trays 14 and 15 are oscillatably held on an arm 17 which is fixed at an end to a tubular spindle 18 which, in turn is pivotally supported in bearings 19 and 20 on the free ends of arms 12 and 13. The lowermost tray 15 seats on arm 17 between a pair of lugs 21 and 22 and diametrically spaced lugs 23 and 24 on the extremities of a bar 24' attached by suitable means to arm 17, as shown in Fig. 4.

The free end of arm 17 carries a pair of fingers 25 and 26 which are attached to the edges of the arm by means of bolts 27 and 28, respectively, and preferably so that the fingers may be selectively spaced from the arm 17, as by means of one or more washers 29 held between the fingers and the arm. As shown in Fig. 4, fingers 25 and 26 straddle the spindle 9 so that during the primary oscillation of the trays, as hereinafter explained, said fingers will strike opposite sides of the spindle and set up counter or secondary oscillations in the movement of the trays. The topmost tray 14 has a cover 14a for preventing the loss of material from said tray during successive sifting operations.

One of the upper trays, or more if necessary, may be additionally supported against dislodgement from the stack as by means of a band 30 extending partially around the tray and provided at its ends with attaching members 31 extended through slots 32 in opposite portions 33 in a fixture 34 which is vertically adjustable on spindle 18 and adapted to be held in selected position by means of a set screw 35 or otherwise. Each of the trays 14 is provided with a screened bottom 36 which plurality of screens in the stack of trays or sieves are of gradually decreasing mesh from 40 the top downwardly in order that the final and most finely divided elements of the material introduced into the topmost tray will be gradually sifted to the receiving tray 15 while the larger particles will be likewise gradually and from stage 50 to stage eliminated.

Motor 5 drives a pulley 37 by means of a belt 38 connected with a driving pulley 39 on motor shaft 40 and said pulley 37 is carried on a spindle 41 supported on the outer end of a bracket 42 rigidly attached to standard 3. A crank 43 is fixed to shaft 41 and is connected at 44 with a connecting rod 45, said connecting rod being, in turn, connected with arm 12, as at 46. Thus the rotation of pulley 37 effects the oscillation of arms 12 and 13 and the stack of trays 14 and 15 and at each extreme of movement one of the fingers 25 or 26 will strike the spindle 9 and thereby set up secondary or countermovements of the material in the trays. The connection 44 of rod 45 may be adjustable on crank 43 if desired as by moving the connecting element in and fixing the same at a selected point in a radial groove 47 on a face of the crank, or otherwise.

In operation, the primary oscillations are set up by the movement of the stacks of trays in alternate directions through the instrumentality of motor driven pulley 37, connecting rod 45, crank 43 and arm 12 when motor 5 is operating, thereby shifting the material carried by trays 14, 14, etc., from one side of each tray to the other side, but if the crank alone were depended upon, as the connecting rod reached dead center positions at either side of its stroke the material would tend to bank up at the end of each stroke against the adjacent margins of the trays, due to the gradual approach to and departure from each extreme of action. By the use of the secondary means, however, at each extreme of movement and twice in each cycle of operation, the fingers 25 and 26, forcibly engage the spindle 9 and thus cause a movement of the material in each tray in a direction opposite to which it has been just previously moved. Hence, twice in each revolution of pulley 37 and crank 43 the material is substantially leveled in the trays 14 and prevented from undue accumulation at any portion of the peripheral wall of any of the trays.

Moreover, the trays being oscillatable on the axis of spindle 18, are primarily oscillatable on the axis of the spindle 9 and secondarily and additionally on the axis of the spindle 18 to an extent of the spacing of the fingers 25 and 26 from opposite sides of spindle 9. Thus, at the end of each primary oscillation not only must the tendency of the trays to continue to move in a given direction be overcome, but, in addition inertia of the trays must also be overcome. Thus, the force of the impact of the fingers 25 and 26 with spindle 9 or any other stationary object serves to provide two shakes of the material for each half cycle of operation and four complete shakes for each complete cycle of operation, and the gradual sifting of the material in successive stages is accomplished more economically and quickly and effectively than is possible when other well known devices for similar purposes are employed.

Thus, it will be observed that I have provided a sifting apparatus which comprises a frame oscillatable about the axis of spindle 9 which carries a support 17 oscillatable about the axis of spindle 18 independently of the movement of the frame, for the purpose of setting up primary and secondary movements of the sieves or trays 14 and the pan 15. Also, the fingers 25 and 26, serve to limit the extent of the movements in opposite directions of the support 17 and the trays carried thereby.

What I claim is:

1. A sifting apparatus comprising: means for supporting a plurality of sieves in a stack, means

for primarily oscillating said sieves as a unit about a vertical axis apart from the common geometric axis of the sieves, and means for secondarily oscillating said sieves on a different axis at the completion of each stroke.

2. A sifting apparatus comprising: means for supporting a plurality of sieves in a stack, means for primarily oscillating said sieves as a unit about a vertical axis spaced from the geometric axis of the sieves, and means for oscillating said sieves on a secondary vertical axis at the completion of each stroke, said last mentioned means including a stationary element and elements movable by the primary means and engageable with the stationary element to limit the secondary movement of the sieves.

3. A sifting apparatus comprising: a base, a frame on said base, means for oscillating said frame on a vertical axis, a supporting member oscillatably carried by said frame and also having a vertical axis spaced from said other axis, and sifting means carried by said supporting member, said sifting means being oscillatable about the axis of said frame and also about the axis of said supporting member, the oscillating axis of said frame and said sifting means being spaced from the geometric axis of the sifting means.

4. A sifting apparatus comprising: a base, a frame oscillatably mounted on said base on a vertical axis, a supporting member oscillatably carried by said frame on a vertical axis spaced from the axis of the frame, sifting means carried by said supporting member, said sifting means adapted to be primarily oscillated about the axis of said frame and secondarily about the axis of said supporting member and having a common geometric axis spaced from their axes of oscillation, and means for oscillating said frame, the said secondary oscillation of said sifting means being effected by reason of the momentum established when said frame is oscillated.

5. A sifting apparatus comprising: a base, a frame oscillatably mounted on said base on a vertical axis, a supporting member oscillatably carried by said frame and oscillatable on a vertical axis spaced from the said axis of oscillation of the frame, sifting means carried by said supporting member, said sifting means being adapted to be primarily oscillated about the axis of said frame, and secondarily oscillated about the axis of said supporting member, said axes of oscillation being spaced from the geometric axis of the sifting means and also, from each other, means for oscillating said frame, the secondary oscillation of said sifting means being effected by reason of the momentum established when said frame is oscillated about the axis of said supporting member, and means for limiting the extent of the oscillations of said supporting member and said sifting member.

6. A sifting apparatus comprising: a frame oscillatable on a vertical axis, means for oscillating the frame, a support oscillatable mounted thereon and arranged to carry a plurality of sifting units, and means for oscillating said frame and said support on the same axis, said support also having an axis of oscillation spaced from that of the frame and on which the support is adapted to oscillate relative to the frame.

7. A sifting apparatus comprising: an oscillatable frame, a support oscillatable on and independently of the frame, said frame and said support having spaced vertical axes of oscillation, means for oscillating said frame, and sifting elements carried by said support, whereby primary

and secondary movements of the sifting elements may be effected, the geometric axis of the sifting elements being off-set from the axes of oscillation of the frame and the support.

8. A sifting apparatus comprising: a frame, 5 means for oscillating the frame, oscillatable both with and independently of the frame on different axes, a sifting means carried by said support and having a geometric axis intermediate the axes of the frame and the support, whereby primary and 10 secondary movements of the sifting means may be effected, and means for limiting the movement of the sifting means relative to the frame.

9. A sifting apparatus comprising: a base having 15 an upright member thereon, a frame oscillatable on said member, a support oscillatable with said frame on said member and separately on said frame, and sifting elements carried by said support, and means for oscillating said frame, whereby counter oscillations of the support and the 20 sifting means is effected.

10. A material sifting apparatus including: a stationary frame, a secondary frame mounted on said stationary frame for oscillation about a first vertical axis, a support oscillatably mounted on a second vertical axis on said secondary frame spaced from and substantially parallel to said first axis and adapted to support a stack of sifting ele- 25

ments and effect counter oscillations of the stack of sieves, the geometrical axis of the sifting elements being substantially parallel to and spaced from said first and second axes.

11. A material sifting apparatus as characterized in claim 10, including means for oscillating the secondary frame.

12. A material sifting apparatus as characterized in claim 10 including means for separately oscillating the secondary frame and the support.

13. A material sifting apparatus as characterized in claim 10 including means for limiting the counter oscillations of the support and the sifting elements carried thereby.

14. A material sifting apparatus comprising: a main frame, a secondary frame oscillatable thereon, a support oscillatably held on the secondary frame and having an axis remote from the oscillating axis of the secondary frame, said support adapted to carry a stack of sifting elements, and means for applying power to and for setting up oscillations of the secondary frame and counter oscillations of the support and the sifting elements, said secondary frame and said support having separate axes of oscillation which are offset relative to the geometric axis of the sifting elements.
